DISTILLATION PROCESS

Wheaton W. Kraft, New York, N. Y., assignor to
 The Lummus Company, New York, N. Y., a corporation of Delaware

Application February 28, 1938, Serial No. 193,168

1 Claim. (Cl. 196—94)

This invention relates to improvements in petroleum refining processes and more particularly to an improved arrangement for the condensing and cooling of the lowest boiling range product from a topping unit.

It is well known that in the operation of topping units, at substantially atmospheric pressure, the amount of uncondensed gaseous material reaches extremely high proportions especially when operating on light or "wild" crude oils. These amounts may range as high as 5% and are frequently in the range of 3-5%, depending upon the availability of cooling water at a suitable temperature and other operating conditions. With a unit having a capacity for 25,000 barrels per day of crude oil, it will be appreciated that the amount of such uncondensed material is very substantial and, even more objectionable, it requires such a large extent of apparatus to handle it, that it becomes a major problem in petroleum refining.

The principal object of the present invention is to provide an improved method for reducing to negligible proportions, the uncondensed gaseous material loss from a topping operation and so absorbing the gas that it can be readily handled in combination with the liquid whereby extensive equipment is not required.

Another object of the invention is to provide an improved process for condensing and sub-cooling the overhead from a topping unit so that the apparatus may be of low cost and will require relatively smaller amounts of cooling water at available temperatures with a maximum efficiency of cooling.

A more specific object of the invention is to operate a topping unit under such pressure, and to condense only so much of the vapors, and to sub-cool only the end product, that higher heat removal efficiency is obtained by a higher mean temperature difference, and the uncondensed gas is reduced to a negligible quantity, and is all handled as absorbed in the liquid end product.

Further objects and advantages of the invention will appear from the following description of a preferred form of embodiment thereof taken in connection with the attached drawing which illustrates diagrammatically that part of a petroleum refining plant which specifically pertains to the condensation and sub-cooling of the lightest fraction from a topping unit.

The topping unit 10, in accordance with my invention, is of any suitable type with the lightest fraction discharged as overhead vapor at 12, the heated crude oil being introduced at 13, and 55

topped crude bottoms product removed at 14. In this case, however, the topping unit 10 is preferably operated under pressure which may be in the neighborhood of fifty pounds per square inch.

5 The overhead vapors are discharged into the heat exchanger 15 which is water cooled by water entering at 16 and discharging at 17.

The heat exchanger 15 is in the nature of a partial condenser and cooler, but has such heat 10 removal capacity that adequate reflux liquid may be obtained. The heat transfer surface is much smaller than usual in this apparatus for even though it handles the entire overhead, the mean temperature difference between the relatively 15 hot vapors and the cooling water is quite large due to the pressure operation and the fact that the reflux is not cooled to end product temperature.

The condensed liquid and uncondensed vapors 20 from the first heat exchanger or partial condenser 15 are then collected in the receiver 18, the liquid level of which is maintained at a desired level by the control 19. The reflux liquid is removed at 20 and pumped into the reflux line 21 to the top of the fractionating column 10. A temperature control is provided at 22 to control the amount of reflux in accordance with the vapor 25 temperature discharging overhead at 12. The reflux, which in usual practice, is several times 30 the volume of final product discharged at 32, is not as cool as is customary but as the reflux is purely a heat removal process, the higher return temperature is not objectionable for more reflux may be returned. The much higher maximum 35 temperature of the overhead, more than balances this higher minimum temperature with the resulting higher mean temperature difference.

The uncondensed gases from the receiver 18 go overhead at 24 under pressure control 25, with 40 the vapor line 24 joined with product line 21a so that the vapors and liquid product are combined and introduced into the final condenser or sub-cooler and absorber 26 through line 27. The final 45 cooler 26 is also water cooled with the inlet at 28 and the discharge at 29.

Pressure control 25 is conveniently inserted in line 24 to maintain the pressure on fractionating column 10 and partial condenser 15 substantially constant and equal. Although condenser 26 is 50 operated at a pressure which may be the same or lower than the pressure on the rest of the system, it is desirable to utilize a pressure control as at 25 to prevent fluctuations in the pressure on the discharge end of the system from affecting the operation in the fractionating column and the

partial condenser. It will be understood, of course, that this pressure control device may be so placed as to maintain both of the condensing stages and the fractionating column under the same pressure.

The higher mean temperature difference in the partial condenser 15 requires a much smaller amount of heat exchange surface than the sub-cooler 26 per unit of heat removed. This is due to the fact that the cooling water entering the sub-cooler 26 is not very much below the necessary temperature of the sub-cooled end product. By virtue of not sub-cooling reflux material, it can be seen that a very great decrease in total heat exchange surface results. This approximately balances the difference in volumes of materials handled.

The resulting end product, which may be a light gasoline is discharged at 32, and is found to contain less than a negligible quantity of uncondensed gas, and this may be directly run to a suitable stabilizing unit. No separation of gas from liquid is required, and the end product has such a relatively small proportion of gas, it may be handled as a liquid without difficulty. No excessively large equipment is required under the circumstances.

As an example of operating conditions under which this process operates, I have used pressures within the fractionating column 10 in the neighborhood of fifty pounds per square inch with equivalent temperatures of approximately 290° F. This compares with normal atmospheric pressure operating temperatures of 175° F. The reflux then returns to the fractionating column at about 140° to 150° F. instead of approximately 105° F.

With cooling water at a minimum temperature of 95° F., it will be seen that in the partial cooler 15, a very large amount of heat may be removed with a relatively high mean temperature difference which would not exist if all of the overhead had to be cooled to 105° F.; cooling the end product only to this low temperature thus makes a direct saving in heat exchange surface.

The pressure operation also permits direct handling of the end product as a liquid and by

reducing the uncondensed gas from 5% to 0.5% or less, approximately ninety per cent of the gas handling equipment can be eliminated. This saves on gas separators, gas conduits, gas holders, and gas compressors, all of which are extremely costly. A typical multiple pass shell and tube heat exchanger for the final cooler 26 is most satisfactory for the required absorption of the liquid and vapor during the sub-cooling.

While I have shown a preferred form of embodiment of my invention, I am aware that modifications may be made thereto and I, therefore, desire a broad interpretation of my invention within the scope and spirit of the disclosure herein, and of the claim appended hereinafter.

What I claim is:

The method of condensing hydrocarbon vapors and gases obtained as an overhead from the fractionation of hydrocarbons under superatmospheric pressure in which the hydrocarbons undergoing fractionation are crude petroleum, and the fractionation treatment is a topping operation, which comprises cooling the vapors and gases to produce a partial condensation thereof, separating the resulting condensate from the uncondensed vapors and gases, returning a sufficient portion of said condensate as reflux for said fractionation, combining the uncondensed vapors and gases with the remainder of said condensate, cooling the mixture to a temperature lower than that of the partial condensation to effect a complete condensation of the vapors and an absorption of the gases in the condensate so that the final product comprises a liquid containing less than 1/2% of uncondensed material, and controlling the pressure at which the uncondensed vapors and gases are separated from the partial condensate in the partial condensation stage independently of the pressure on the final condensation and cooling stage, the pressure on the partial condensation stage being substantially equal to the pressure of fractionation and higher than the pressure on the final condensation and cooling stage.

WHEATON W. KRAFT.
